UNITED STATES PATENT OFFICE

CHARLES W. SHEVLIN, OF CHICAGO, ILLINOIS, ASSIGNOR TO FRANK M. HARKER, OF WILMETTE, ILLINOIS

AWNING

Application filed May 23, 1928. Serial No. 279,888.

My present invention relates to improvements in awnings and has for its objects the provision of an awning of increased stability and dependability in service and which, by reason of having its corners or edges held and protected, will withstand the action of winds more effectively and will be subject to less damage by wear in ordinary service.

I have also had as an object of my invention the provision of an awning structure consisting of a housing and very simple additional equipment which will permit of the rolling up and complete housing of the fabric or curtain portion of the awning when not in use so that the awning installation need not be taken down and stored during the seasons of the year in which such structures are not used.

I accomplish the foregoing objects by means of the structure illustrated in the accompanying drawings in which—

Fig. 1 is a perspective of a window having an awning embodying my invention installed in connection therewith.

Fig. 2 is a central vertical transverse section of the structure shown in Fig. 1 on line 2—2 thereof, except that in Fig. 2 the awning is retracted within its housing and the stays are folded so as to bring the guides adjacent to or within the window opening.

Fig. 3 is a section similar to that shown in Fig. 2 except the stays are in extended position and the awning has been drawn down into the guides and the side flaps thereof secured to the stays.

Fig. 4 is a horizontal cross section through the housing on line 4—4 of Fig. 3.

Fig. 5 is a cross section of a guide showing the manner in which the edge of the awning is related thereto and secured therein.

Fig. 6 is a fragmental detail, partially in section, of the lower end of a guide showing the relation of the corner of the awning thereto when the awning is in extended position.

Fig. 7 is a fragmental detail, partially in section, of the upper end of a guide showing its assembly with the housing and the relation of the corner of the awning when the awning is housed or in retracted position.

Fig. 8 is a front view of a form of bracket employed for holding the awning housing in position.

Fig. 9 is a cross section through the bracket shown in Fig. 8 showing the relation of the awning housing thereto.

Fig. 10 is a perspective detail of a bracket for securing a stay to the window casing.

Fig. 11 is a perspective similar to Fig. 1 showing my invention applied to a center break instead of a hood awning.

Fig. 12 is a fragmental sectional detail similar to Fig. 2 but of the center break awning shown in Fig. 11, and

Fig. 13 is a detail of a form of snap button for suitably securing the lower edges of the sides of a hood awning to the stays.

Similar reference characters have been employed to designate similar parts throughout the several views.

The awning housing comprises end plates 15, as most clearly shown in Figs. 4 and 9, of a more or less circular configuration having an outwardly extending flange 16 around the sides and top. About the flanges 16 and between the end plates at opposite ends of the window frame is an enclosing or cover plate 17 which does not extend across the bottom and thereby provides an opening or fenestra through which the awning is retracted into the housing and withdrawn therefrom. This structure is secured at or adjacent the top of the window frame by lag screws 18, which pass through the cover plate 17 and flanges 16 of the end plates into the window frame, as shown in Figs. 2 and 4, or by a headed through bolt 19 and nut 20 in connection with plate 21, shown in Figs. 8 and 9, which plate is horizontally slotted, at 22, to permit of some adjustment. The plate 21 is peculiarly applicable to metallic window frames to which it can be secured by rivets or screws passing through corner bores 23.

Pivoted to the end plates 15 at a point 24 at the rear of their lower edges are guides 25. These guides, as best shown in Fig. 5, are formed with a square section having an inwardly opening slot 26. The form of the section of these guides is not important except that whatever form is determined upon

should provide the interior recess and the inwardly opening slot. The outer portion or wall 27 of the guide is extended sufficiently at the top to pivot the same to the end plate 15, as shown in Fig. 7. The edges of the front or main portion of the awning fabric 28 extend through the slots 26 and into the recess in the guides on opposite sides of the window and are there provided with suitable means for retaining them in the recesses.

In Fig. 5 I have shown such retaining means as consisting of washers or grommet plates 29 provided on both sides of the awning fabric 28, through which are driven a pin 30 of suitable length to easily slide in the recess in the guide and to prevent the withdrawal of the awning fabric through the slot 26. The lower end of the guides are closed in any desired way as, for instance, by extending the outer wall 27 and bending it beneath the guide so that it will extend beyond the inner face of the guide to permit of its inward extension being bent downwardly into a tang or lug, as shown at 31 in Fig. 6.

I have also further reinforced the lower end of the guide with a strap 32, an end whereof is extended from the back wall of the guide to provide an ear 33 for pivotally attaching a stay member 34. The retaining pins 30 are disposed at suitable intervals along the longitudinal edges of the front or main awning fabric 28 and the bottom of this fabric is turned over and hemmed, as at 34, for receiving a suitable rail or batten 35. The ends of the batten 35 are extended slightly beyond the edges of the awning fabric and sufficiently close to the inner face of the outer guide wall 27 to engage the bottom of the end plates 15 when the awning is rolled into the housing and thereby prevent the awning from being retracted so far into the housing that it cannot be readily withdrawn therefrom. This relation is shown in Fig. 7.

I have shown washers or grommets 29 and a pin 30 located so that the pin will pass through the end of the batten whereby the relation of batten and awning fabric is dependably maintained.

I have pierced both ends of the awning and batten closely adjacent the line at which they enter the guides and have disposed in this hole a ring or loop 36 which will engage the tang 31 by gravity when the awning is drawn down to the outer ends of the guides. When it is desired to house the awning these rings or loops 36 must be manually disengaged from the tangs 31.

To secure the bottom of the awning in any desired position from the window I provide stays consisting of two members 34 and 34a. Each of these members may be conveniently made of channel metal, the sides of the abutting ends of which are extended and pierced to form the hinges 37, as shown

in Figs. 1, 2, 3, 11 and 12. The inner ends of the inner stays 34a are pivoted between the ears or lugs of brackets 39, shown most completely in Fig. 10, which brackets are preferably secured to the front faces of the side rails of the window frame so that the stays 34 and 34a may be manually folded at the hinge 37 to bring the guides 25 closely adjacent the window frame and generally within the window opening, as shown in Figs. 2 and 12.

The awning may be most conveniently manipulated to roll it into and out of the housing when the stays are folded, and the guides are close to the window frame. After the awning has been withdrawn from the housing and the rings or loops 36 have engaged the extensions or ears 31, it is inclined with respect to the window and dependably maintained in such inclined position by unfolding the stays 34 and 34a.

For retracting the awning into the housing any convenient means may be employed. I have shown in Fig. 4 such a means consisting of a hollow roller 40 to which the upper or inner end of the awning is attached. The roller 40 is permanently closed at one end, from the center of which permanently closed end extends a pin 41, which is journaled in a perforation or bore in one of the end plates 15 of the housing. A coiled spring 42 is inserted within the tube 40 and its inner end is attached or secured to the wall of the tube or roller. The opposite end of the spring 42 is secured to a disk 43 which is journaled to rotate in and close the opposite end of the tube or roller 40. From the center of the outer face of the disk 43 extends a pin 44 of angular section which extends through an opening of similar section in the opposite plate 15 of the housing. The housing and the roller are preferably assembled before the housing is fixed to the window casting as the parts of the structure are simple and dependable in action and will function indefinitely when once installed.

I have not complicated the drawing by a showing of a pull string or other means for drawing the awning down as there are a number of such means well known, any of which may be employed.

When so desired the awning may have stitched to its edges, side or end pieces 45, which may be folded, as schematically shown in Fig. 1, and rolled into the housing and when the awning is drawn out the lower edges of these side or end pieces may be secured to the stays in any desired manner, such as by snap buttons 46, as shown in Fig. 3 and detailed in Fig. 13.

For certain services what are known as center break awnings are convenient and popular. My invention may be equally well applied to such a style of awning, as shown in Figs. 11 and 12, and the only changes re-

quired from the structure heretofore described is to divide the guides 25 at the desired point and secure the portions of the guides together by hinges 47. In such case it is also desirable to provide means such as a hook and eye 48 for securing the lower end of the upper guide section closely into the window frame. With center break awnings I also prefer to provide an additional cross batten 49 which will come at the lower ends of the upper guide sections when the awning is extended. Battens may also be placed advantageously at other portions than the bottoms and centers of the awnings in both types where particularly severe service is anticipated. The hood and center break types of awnings are very seldom combined, but as is easily appreciated, such combination would in no essential respect alter the structure or principles of operation heretofore described.

The housing guides and stays are such simple structures that their permanent attachment to the window causes no inconvenience, and, in fact, is rarely, if ever, noticed, so that when the awning has once been installed it need not be removed between seasons. It is obvious that the presence of the guides, stays and battens greatly strengthen the awning structure and render its operation more secure and dependable.

Having described my invention what I claim as new and desire to secure by Letters Patent is:

35 1. An awning comprising a housing having a longitudinal opening therein, a roller revolvably mounted within said housing, longitudinally recessed guide members pivoted to said housing at the ends of the said longitudinal opening therein, a fabric awning element, one end whereof is secured to said roller and the edges whereof extend into the recesses in said guides, and means carried by the edges of said fabric awning element to prevent its lateral withdrawal from said guides.

2. An awning comprising a housing having a longitudinal opening therein, a roller revolvably mounted within said housing, longitudinally recessed guide members pivoted to said housing at the ends of the said longitudinal opening therein, a fabric awning element, one end whereof is secured to said roller and the edges whereof extend into the recesses in said guides, means carried by the edges of said fabric awning element to prevent its lateral withdrawal from said guides and stays pivotally related with the unattached ends of said guides for maintaining said guides at an inclined relation with the building with which said awning structure is assembled.

3. An awning comprising a housing having a longitudinal opening therein, a roller revolvably mounted within said housing,

longitudinally recessed guide members pivoted to said housing at the ends of the said longitudinal opening therein, a fabric awning element, one end whereof is secured to said roller and the edges whereof extend into the recesses in said guides, means carried by the edges of said fabric awning element to prevent its lateral withdrawal from said guides and hinged foldable stays pivotally related with the unattached ends of said guides for securing the lower ends of said guides in desired position.

4. An awning comprising a revoluble roller, mountings for the ends of said roller, longitudinally recessed guide members pivoted to said mountings, a fabric awning element, one end whereof is secured to said roller and the edges whereof extend into the recesses of said guides and means carried by the edges of said fabric awning element slideable within the recesses of said guides for preventing the lateral withdrawal of the edges of said awning element from said guides, and stays pivoted to the unattached ends of said guides.

5. An awning comprising a revoluble roller, mountings for the ends of said roller, longitudinally recessed guide members pivoted to said mountings, a fabric awning element one end whereof is secured to said roller and the other end whereof is provided with a transverse batten, the edges of which awning element and batten extend into the recesses in said guides and means carried by the edges of said fabric awning element slideable within the recesses of said guides for preventing the lateral withdrawal of the edges of said awning element from said guides, and stays pivoted to the unattached ends of said guides.

6. In an awning a housing having a longitudinal opening therein, hollow guides with inwardly opening slots pivoted to said housing at the ends of said opening, a roller revolvably mounted in said housing, a fabric awning element one end whereof is secured to said roller and the edges whereof extend through the slots in said guides, means secured to the edges of said fabric awning element longitudinally movable within said guides for preventing the lateral withdrawal of the awning through said slots, and stays for securing the unattached ends of said guides in a plurality of positions with respect to the structure with which it is assembled.

7. In an awning a housing having a longitudinal opening therein, hollow guides with inwardly opening slots pivoted to said housing at the ends of said opening, a roller revolvably mounted in said housing, a fabric awning element one end whereof is secured to said roller and the edges whereof extend through the slots in said guides, means secured to the edges of said fabric awning element longitudinally movable within said

- guides for preventing the lateral withdrawal of the awning through said slots, stays for securing the unattached ends of said guides in a plurality of positions with respect to the structure with which it is assembled, and side fabric members secured to and extending from said fabric awning element and means for securing the lower edges of said side members detachably to said stays.
8. An awning comprising a fabric sheet, a roller to which one end of said fabric sheet is attached and upon which it is rolled, a housing for said roller having a longitudinal opening therein, guide members pivoted to said housing at the ends of said opening, said guide members being hinged intermediate their ends, transverse battens carried by said fabric sheet, the ends whereof and the edges of said sheet being provided with means co-operable with said guides to prevent the lateral disengagement between said sheet and battens and guides and stays for securing the unattached ends of said guides.
9. An awning comprising a housing having a longitudinal opening therein, a roller revolvably mounted within said housing, guide members pivoted to said housing at the ends of the said longitudinal opening therein, a fabric awning element, one end whereof is secured to said roller and means carried by the edges of said fabric awning element slidably co-operating with said guides to prevent its lateral withdrawal therefrom.
10. An awning comprising a housing consisting of end plates having flanges in the facing surfaces thereof and a cover plate extending between said end plates and over said flanges, said sheet and flanges being bored for the passage of means for securing said plates in position and the housing to the window frame, said housing having a longitudinal opening therein, a roller revolvably mounted within said housing, longitudinally recessed guide members pivoted to said housing at the ends of the said longitudinal opening therein, a fabric awning element, one end whereof is secured to said roller and the edges whereof extend into the recesses in said guides, and means carried by the edges of said fabric awning element to prevent its lateral withdrawal from said guides.

CHARLES W. SHEVLIN.
